UNITED STATES PATENT OFFICE.

EDGAR D. STEWART, OF NEWARK, NEW JERSEY.

SWITCH-SHIFTER.

SPECIFICATION forming part of Letters Patent No. 453,250, dated June 2, 1891.

Application filed December 24, 1890. Serial No. 375,750. (No model.)

To all whom it may concern:

Be it known that I, EDGAR D. STEWART, a citizen of the United States, residing at Newark, Essex county, New Jersey, have invented 5 certain new and useful Improvements in Switch-Shifters, fully described and represented in the following specification and the accompanying drawings, forming a part of the same.

10 This invention relates to a particular means of operating a switch-shifting device for street-cars, consisting, primarily, in a handle mounted over the platform of the car and provided with a grooved cam and a cord attached to the longer side of the cam and extended to the shifting-arm.

15 The invention will be understood by reference to the annexed drawings, in which—

Figure 1 is a side elevation of a car provided with my improvement. Fig. 2 is a plan of the track with a portion of the switch-shifting attachments and a dotted outline representing the body of the car. Fig. 3 is a vertical section of the pit by the side of the 20 track with the switch-shifter therein. Fig. 4 is a cross-section at the right hand end of such pit. Fig. 5 is a plan of the pit with the cover and the treadles removed. Fig. 6 is an elevation of the car-platform viewed from 25 the inner side. Fig. 7 is an elevation of the box carrying the actuating-handles and their connections to the bottom of the platform, with its cover removed. Fig. 8 is a plan of 30 the same, and Fig. 9 is a cross-section where 35 hatched of the same on line $x-x$ in Fig. 7.

A is the body of the car; B, the platform; C, the dash-board; E, the rails of the main track; F, the turn-out, and G the switch-point.

40 H is the cover of the pit at the side of the track, in which two openings are shown containing treadles I and J. Such treadles are arranged to operate in the usual manner when pressure is exerted upon them to shift the 45 switch point G, the treadles resting upon lever-arms n, attached to a rock-shaft o, which is connected by means of a lever p and link q with the switch-point G. The treadles act in opposition to one another, and two arms are 50 attached to the car to press upon either treadle for shifting the switch in the required direction. The arms a are pivoted upon the

frame of the car and actuated by connections b with handles c, which are shown herein mounted upon a box d, attached to one side 55 of the dash-board C. The arms a are hinged by pivots e to the frame of the car and are provided at their ends with rollers f, one of which is shown in contact with the treadle I in Fig. 1. The springs g hold the lever-arm 60 normally raised with the rolls f clear of the track, and the movement of the handle c operates to turn the lever downward and to press the roller f toward the track in a line with the treadle as the car approaches the 65 same. I attach a spirally-grooved cam h to each of the levers c and wind a cord b upon the cam, connecting the end of the cord with the longer side of the cam and with the lever-arm a. The cam thus operates to turn the 70 arm with rapidity when the handle is first moved and afterward to hold it firmly while in contact with the treadle. The pulleys i are fixed in the box d, with guards l adjacent to the same to hold the cord upon the pulley 75 as the spiral cam is rotated. The pulleys j are fixed in ears at the bottom of the box, which ears project through the floor B of the platform to lead the cords beneath the same in the direction of the arms a. Both ends of 80 the car would be provided with the arms a and their actuating mechanism if the car were reversible, and the car in Fig. 1 is shown thus provided with arms at both ends, only one of those at the right-hand end being wholly 85 visible, as both are represented in an elevated position.

The handle may be provided with locking devices, if desired; but I have not shown the same herein, as the essential part of my invention is the grooved cam having attached thereto a flexible connection with the shifting-arm a. The treadles I and J may be arranged one upon each side of the rail E, or both upon the outside, or both upon the inside, as shown in the drawings, and the arms a would be respectively arranged to strike the treadles I and J whatever their location beneath the car. Where the actuating-handle is arranged over a platform which is provided for the operator, it is obviously immaterial whether the handle be mounted upon the dash-board or otherwise sustained over the platform.

Having thus set forth the nature of my invention, what I claim herein is—

1. The combination, with a car, of an arm pivoted beneath the frame of the car, means for holding the arm normally raised, a handle mounted over the platform of the car and provided with a cam, and a cord attached to the longer side of the cam and connected with the said arm, as and for the purpose set forth.

2. The combination, with a car, two arms *a*, pivoted beneath the frame of the same, and means for holding the said arms normally raised, of the columnar box *d*, secured upon the car-platform, the handles *c*, pivoted within the box and provided with cams *h* upon their opposite sides, cords *b*, connecting the cams with the arms *a*, and the rollers *j*, projected through the platform, substantially as herein shown and described.

3. The combination, with a car, two arms *a*, pivoted beneath the frame of the same, and means for holding the said arms normally raised, of the columnar box *d*, secured upon the car-platform, the handles *c*, pivoted within the box and provided with cams *h* upon their opposite sides, cords *b*, connecting the cams with the arms *a*, the rollers *j*, projected through the platform, and the guide-rollers *i*, intermediate to the cams and the rollers *j*, substantially as shown and described.

In testimony whereof I have hereunto set my hand in the presence of two subscribing witnesses.

EDGAR D. STEWART.
